UNITED STATES PATENT OFFICE

WALTER HENGST, OF CHEMNITZ, GERMANY

CONTROL BUTTON FOR THREAD BOBBINS

Application filed December 18, 1929. Serial No. 415,048.

This invention relates to a checking button, which is placed on the bobbin tubes and cardboard sleeves and serves for marking the threads to be worked and wound on the bobbins and cardboard sleeves for further treatment so that an effective and thorough control and a better regulated working operation are ensured.

Similar arrangements for the same purpose are known, for example wooden buttons with differently coloured heads and split, slightly resilient pins, but with these known means it was not possible to mark the threads differently as is desirable for an accurate control and regulated manufacture.

These disadvantages are overcome by the present invention which is illustrated by way of example in the accompanying drawing, in which:

20 Fig. 1 shows in section the control button inserted in the bobbin.

Fig. 2 is a top plan view of Fig. 1.

Fig. 3 shows the lower part of the control button in side elevation.

Fig. 4 is a top plan view of Fig. 3.

Fig. 5 shows the top part of the button in side elevation.

Fig. 6 is a top plan view of the top part of the button.

30 One or more spring arms *b* are fixed to the bottom *a* of the button, said arms serving to fasten the button on the bobbin or cardboard sleeve. The circular slightly domed disc of the lower part *a* is provided with two diametrically opposite semi-circular or other suitably shaped indentations *c*, *d*.

The upper part, Figs. 5 and 6, has the shape of a frame of curved cross section with 40 two diametrically opposite tongues *e*, *f* bent downwardly and inwardly adapted to be inserted through the indentations *c* and *d* of the lower part thus producing a secure connection between the two parts when the upper part is turned in relation to the lower part

45 through a quarter of a revolution, after the marking plate *g* made of celluloid, paper or other suitable material has been placed between the two parts.

50 By this means it is possible for the user to

himself change the marking plates which are either ready printed or arranged for writing. The control buttons may be supplied finished and closed.

In order to obtain the greatest possible 55 and most easily distinguishable marking, both the marking plates *g*, as well as the frame shaped upper part may be made in different colours and the plates *g* may, as already stated, be ready printed or arranged 60 for taking writing.

In order to obtain a good hold of the control buttons in the bobbin tubes, the control buttons are made of a hollow shape, adapted 65 to the bobbin tubes.

I claim:—

1. A control button for thread bobbins comprising in combination a lower disc shaped part having two diametrically opposite indentations in its edge, spring arms 70 extending from said lower part designed to be inserted in the thread bobbin, an upper frame-shaped part colored corresponding to the thread, and downwardly and inwardly bent tongues arranged on said upper part 75 adapted to engage with said indentations of said lower part.

2. A control button as specified in claim 1, comprising in combination with the upper and the lower part, a control plate of suitable material and arranged for marking and adapted to be inserted between said upper part and said lower part.

In testimony whereof I affix my signature.

WALTER HENGST.
